ADJUSTABLE DESK TOP AND BOOK
COMPARTMENT

William J. Bargin, Waukegan, Ill.

Original application July 26, 1939, Serial No.
286,699. Divided and this application March
13, 1940, Serial No. 323,800

5 Claims. (Cl. 155—4)

This invention relates to school desks and is a division of my copending application, Serial No. 286,699, filed July 26, 1939, for Offset pedestal desk.

An object of this invention is to provide an improved desk including a book holding compartment wherein the desk or top is hinged to the book compartment and is frictionally held against swinging movement.

Another object of this invention is to provide in combination, a book compartment and a desk element or top which is hingedly secured thereto, the book compartment being so constructed as to prevent the placement of an excess of books, papers or the like in the forward portion of the compartment so as to place a strain on the hinge for the desk or top.

A further object of this invention is to provide a desk with a hinged top and means to limit the raising of the top with the strain on the hinge, while at the same time resisting torsional strain on the top supporting means.

Embodying the aforesaid aims and others which may hereinafter appear, the invention consists of the novel construction, combination and arrangement of parts as will be more specifically referred to and illustrated in the accompanying drawing, wherein is shown an embodiment of the invention, but it is to be understood that changes, variations and modifications may be resorted to which fall within the scope of the invention as claimed.

In the drawing:

Figure 1 is a vertical section of a book compartment and top constructed according to an embodiment of this invention.

Figure 2 is a sectional view taken on the line 2—2 of Figure 1.

Figure 3 is an enlarged fragmentary sectional view taken on the line 3—3 of Figure 2.

Figure 4 is a sectional view taken on the line 4—4 of Figure 3.

Figure 5 is a fragmentary sectional view taken on the line 5—5 of Figure 3.

Referring to the drawing, numeral 10 designates generally a book compartment or holder comprising end walls 11 and 12. The end wall 11 has at the rear lower corner thereof a stem or supporting member 13 which is adapted to engage a stationary support as more specifically set forth in my copending application filed of even date herewith and as set forth in my application, Serial No. 286,699. The book holder or compartment 10 has a metal box disposed between the end walls 11 and 12 thereof which includes a bottom wall 14, a front wall 15 and a rear wall 16. The box or holder comprising the walls 14, 15 and 16 is adapted to be made out of sheet metal and the bottom wall 14 is provided

with longitudinal corrugations 17 which provide a reinforcing means for the bottom wall 14. The front wall 15 extends upwardly and rearwardly from the forward end of the bottom wall 14 and is transversely curved as shown in Figure 1. The book compartment or box comprising the walls 14, 15 and 16 engages between the end walls or members 11 and 12 and these end members 11 and 12 are each provided with inwardly projecting marginal flanges 18 within which the sheet metal box comprising the walls 14, 15 and 16 is adapted to engage.

The front wall 15 at its upper end extends rearwardly as at 19 and is then bent forwardly upon itself to form a reinforced relatively narrow top wall for the book compartment. The top wall which is formed by the reverted portion 19 engages a pair of inwardly projecting lugs or ears 20 and 21 which are carried by the end members 11 and 12, respectively, and the top wall 19 is secured to the ears or lugs 20 and 21 by fastening devices 22 in the form of rivets or the like.

A desk element or top 23 engages the open upper portion of the book holder or compartment 10 and is hingedly secured thereto by a pair of substantially L-shaped hinge arms or members 24. The hinge members 24 are secured one to each of the end members 11 and 12 on the inner side thereof and each hinge member 24 comprises one leg 25 which is provided with an elongated base bar 26 engaging the under side of the top member 23.

The base bar 26 is formed with an upwardly projecting rib or bead 27 which engages in a channel 28 formed in the under side of the top 23. Fastening devices 29 engage through the base bar 26 and fixedly secure the leg 25 to the top 23. Each hinge arm 24 also includes a second angularly disposed leg 30 which is provided with a substantially annular head 31. The head 31 is provided with an axial opening 32 through which a pivot bolt 33 engages. The pivot bolt 33 engages through one of the end members 11 and 12 and also engages a plate 34 forming an inner wall for a housing within which the arm 24 engages. An inwardly projecting flange 35 is formed as shown in Figures 3 and 4 with the inner side of the end member 12 and the plate 34 is secured to the flange 35 by fastening devices 36. The arm 24 engages between the plate 34 and the end wall 12 and in order to provide a means whereby the arm 24 may be frictionally held against turning, I have provided an inner resilient washer 37 which is interposed between the inner face of the plate 34 and the adjacent side of the annular head 31.

A second resilient washer 38 engages against the opposite or outer side of the head 31 and against the inner side of the end wall 12. Either or both of the washers 37 and 38 may be made

out of rubber or similar resilient material and when the plate 34 is secured to the flange 35, the two washers 37 and 38 will be compressed against the opposite sides of the head 31 and thus form a resilient means which will resist turning of the head 31 on the pivot member 33.

The top 23 at its forward edge has secured thereto, a bumper generally designated as 39. This bumper 39 comprises a metal core 40 in the form of an elongated flat bar which is embedded in a rubber or yieldable cover 41. The bar 40 is provided with a plurality of inwardly projecting lugs 42 which are secured by fastening devices 43 to the under side of the top 23. A pencil or art box support 44 is secured to the outer side of the end member 11 by means of angle members 45. The pencil box support 44 is open at the top and is also open at its outer side, being provided with an elongated bar 46 extending between the front and rear walls 47 and 48 thereof.

An art box of yieldable construction is adapted to slidably engage in the support 44 and to be moved laterally thereof as set forth in my co-pending application, Serial No. 286,699.

In the use of this book compartment and desk structure, the stem 13 is adapted to be vertically adjusted as set forth in my copending application and the book holder 10 is adapted to receive books, papers or other articles which may be inserted in the holder by raising the top 23. The top 23 will remain in its raised position, which is the position shown in dotted lines in Figure 3 by reason of the resilient holding washers 37 and 38 which engage the heads 31 of each hinge arm 30. The end members 11 and 12 are adapted to be cast out of metal and the stem 13 is adapted to be cast with the end member 11. The walls 14, 15 and 16 are formed out of sheet metal and engage within the flanges 18 formed about the marginal edges of these end members 11 and 12. By reason of the rearwardly projecting top wall 19, it will not be possible for a student to insert any books or other material in the holder 10 which might project above the upper forward edge of the holder 10. In this manner, the hinge members 24 will not be subjected to any undue strain when the top 24 is lowered.

The top 24 on the under side thereof is provided with a pair of yieldable cushioning members 49 which are adapted to engage the rear portions of the end members 11 and 12 when the top 23 is in closed position.

What I claim is:

1. A combined desk top and book compartment comprising a box provided with front, rear and bottom walls and a pair of end walls, a rearwardly projecting top wall extending from said front wall and terminating at its rear edge forwardly of said rear wall, means securing said top wall to said end walls, a top member, a pair of L-shaped hinge members each having one leg thereof fixed to said top and having the other leg thereof projecting inwardly beneath said top wall, an inwardly projecting flange carried by each end wall, a plate fixed to said flange and forming therewith a housing for a hinge member, a pivot engaging through an end wall, said other leg of an L-shaped hinge member and through said plate, and means carried by said pivot for yieldably resisting turning of a hinge member relative to a pivot to thereby hold said top member in a selected position relative to said box.

2. A combined desk top and book compartment comprising a box provided with front, rear and

bottom walls and a pair of end walls, a rearwardly projecting top wall extending from said front wall and terminating at its rear edge forwardly of said rear wall, means securing said top wall to said end walls, a top member, a pair of L-shaped hinge members each having one leg thereof fixed to said top and having the other leg thereof projecting inwardly beneath said top wall, an inwardly projecting flange carried by each end wall, a plate fixed to said flange and forming therewith a housing for a hinge member, a pivot engaging through an end wall, said other leg of an L-shaped hinge member and through said plate, and a pair of yieldable washers about said pivot and engaging on opposite sides of said other leg for yieldably resisting turning of a hinge member relative to a pivot to thereby hold said top member in a selected position relative to said box.

3. A combined desk top and book compartment comprising a pair of oppositely disposed end wall forming members provided with inwardly extending flanges, a support connected to one of said members, a box formed of a bottom and front and rear walls arranged between said end walls upon said flanges, said front wall extending rearwardly from its lower to its upper end and provided at its upper end with a rearwardly directed extension forming a top wall, means for securing said extension to said members, a top member arranged over said wall forming members and extended forwardly from the upper end of said front wall, a pair of hinged means fixed at one end to said top member and having their other ends arranged in the forward portion of said box below said top wall, housing means for the said other ends of said hinged means, means for pivotally connecting the said other ends of the hinged means to said housing means, and braking means arranged in said housing means for said hinged means.

4. In combination, a desk top, a pair of oppositely disposed upstanding spaced parallel end wall forming members arranged below said top and provided with inwardly extending flanges at their lower ends, an element arranged below said desk top and formed of a horizontal portion, a front vertical portion and a rear vertical portion providing respectively a bottom and front and rear walls, said element arranged between said members and having its bottom wall seated on said flanges, said front wall being provided at its upper end with a rearwardly directed extension forming a top wall, angle-shaped hinge members depending into said element fixedly secured at one end to the lower face of said desk top, means for pivotally connecting the other ends of said hinge members to said wall forming members, braking means for said hinge members at the said other ends thereof, means for securing said extension to said end wall forming members, and said hinge members, end wall forming members and element correlating to form a normally closed book compartment, and supporting means for an end wall forming member.

5. The invention as set forth by claim 4 having the front portion of said element extended rearwardly from its lower to its upper end, the horizontal portion of said element corrugated and said desk top extended laterally from said end wall forming members and from the front and rear upstanding portions of said element.
